CLAIM

The ornamental design for a computer case as shown and described.

DESCRIPTION

FIG. 1 is a perspective view of a part of the computer case according to the present design;

FIG. 2 is a front view of a part of the computer case according to the present design;

FIG. 3 is a rear view of a part of the computer case according to the design;

FIG. 4 is a left view of a part of the computer case according to the present design;

FIG. 5 is a right view of a part of the computer case according to the present design; and,

FIG. 6 is a top view of a part of the computer case according to the present design.

The broken lines in the drawings illustrate portions of the computer case which form no part of the claimed design.

1 Claim, 6 Drawing Sheets(56)
